UNITED STATES PATENT OFFICE.

BENJAMIN W. LEVITAN, OF NEW YORK, N. Y.

FRAMEWORK OF BUILDINGS.

1,419,868.

Specification of Letters Patent. Patented June 13, 1922.

Application filed July 25, 1918. Serial No. 246,659.

To all whom it may concern:

Be it known that I, BENJAMIN W. LEVITAN, a citizen of the United States, and a resident of the borough of Manhattan, in the 5 county, city, and State of New York, have invented a certain new and useful Improvement in the Framework of Buildings; and I hereby declare that the following is a full, clear, and exact description of the same, reference being made to the accompanying drawings, forming part of this specification.

This invention relates to improvements in the framework of buildings which have metal frames or frames mainly formed of 15 metal, the chief object of the invention being to facilitate the preparation and transportation of materials for, and the erection, removal and re-erection of, very large one-story buildings suitable for use, for example, 20 in housing aeroplanes, balloons, hydro-aeroplanes, war munitions, supplies, troops, horses, ordnance, ambulances, etc., and as mess-halls, field-hospitals, armories, railway stations, exhibition-buildings, tabernacles, 25 pavilions; convention-halls, amusement-halls, and shelters for many other large objects and stores of materials. The invention consists of framework forming part of a building and including a series of frame-units 30 such as is described in, and defined in the claims of, this application.

On the accompanying three sheets of drawings, like reference-numerals designating like parts in different views:

Fig. 1 is a diagrammatic side elevation of 35 a frame-unit, comprising uprights, stays and rafters;

Fig. 2, a view from one end of the frame-unit, of a fragment of a stay attached to 40 an anchor;

Fig. 3, a side and sectional view of fragments of stays attached to an anchor;

Fig. 4, a side view of a part of a hanger and fragments of rafters, stays and roofing;

Fig. 5, a vertical section of this hanger; and other parts, on the plane x , x , Fig. 4;

Fig. 6, an underside view of the hanger and fragments of rafters shown in Fig. 4;

Fig. 7, a side view of fragments of one 50 of the uprights and some of the other parts of the frame-unit;

Fig. 8, a side elevation of another hanger and fragments of a stay, a rafter and roofing, the rafter being attached to the stay 55 by the hanger.

Fig. 9, a vertical section of this hanger

and of the stay and rafter, on the plane y , y , Fig. 8;

Fig. 10, a diagrammatic side elevation of part of a framework comprising a series of 60 frame-units;

Fig. 11, an end elevation of a building embodying the invention;

Fig. 12, a diagrammatic side elevation of a duplex frame-unit; and

Fig. 13, a plan of walls shown in elevation in Fig. 12.

All of the frame-units of a series are alike, but the invention may be embodied in buildings of many different sizes and the frame-units of any building differ in size from those of a building of different width. Yet whatever may be the size of the frame-units of any series the construction of each is the same as, or similar to, that of one of the 75 frame-units herein described and defined in the claims.

Each frame-unit resembles a truss in character, the frame-units of any building extending from side to side thereof and each 80 being attached to the next unit or units of the series by beams which extend lengthwise of the building. Therefore, Figs. 1 and 12 represent not only side elevations of two frame-units but also end elevations of two 85 series of frame-units. A building of which a series of frame-units like that illustrated in Fig. 1 forms a part, may cover a very wide unobstructed area. The length of the area depends on the length of the series of 90 frame-units which is included in the framework, and which may consist of a large or small number of frame-units, spaced at suitable distances, for example twenty feet, apart. Fig. 11 shows an end of such a 95 building.

The pair of uprights 1 and 2, which must be rigid and very strong, are preferably steel beams such as are commonly called H-beams, for while uprights of other forms, such as 100 tubes filled with concrete, or lattice-beams, may be used, the H-beams are especially suitable and are to be obtained more readily and at less cost than are other suitable beams or columns. These uprights stand on solid 105 foundations to which they should be firmly fastened and which may be rock or masses 3 and 4 of concrete embedded in the ground. The uprights shown are composed of bases 5 and 6 and main portions pivotally connected to the bases by pins 7 and 8. The bases 5 and 6 may be attached by bolts 9

to metal bars 10 embedded in the foundations, or be otherwise fastened to the foundations. The uprights are stayed so as to prevent them from buckling or bending inward (towards one another) under the action of the stresses which they are required to bear.

The stays, which are tension-devices, may be wire ropes or chains or rods or eye-bars, yet it is especially desirable to use wire rope rather than stays of any other form, because it is less troublesome if not also less expensive to procure and transport large quantities of wire rope and to convert it into stays where they are wanted, than it would be to make use of stays of any other commonly known kind. Each or any stay may be a single cable, chain or rod, or may consist of a group of tension-devices arranged in such relations as will enable them to act as a composite stay. Some of the stays, called herein outer stays, extend from the uprights outward and downward to anchors, to which they are secured at their lower ends. The outer stays 11 and 12 extend from the upright 1 to the anchor 13, and the outer stays 14 and 15 extend from the upright 2 to the anchor 16, each of these stays having eyes at its ends and including means such as a turnbuckle or turnbuckles by which it may be made taut. The anchors 13 and 16 may be large rocks or masses of concrete. Staples 17 and 18 fixed in the anchor 16 pass through the eyes at the lower ends of the stays 14 and 15, and staples fixed in the anchor 13 pass through the eyes at the lower ends of the stays 11 and 12, but obviously other means might be used to fasten the stays to the anchors. The staples 19 and 20 which connect the stays 11 and 12 to the anchor 13 are like the staples 17 and 18, shown in Figs. 2 and 3. The brackets 21 and 22 riveted to the upright 1 and engaged by the eyes at the upper ends of the stays 11 and 12 respectively, and like brackets 23 and 24 riveted to the upright 2 and engaged by the eyes at the upper ends of the stays 14 and 15 respectively, connect the stays to the uprights.

The stays 25 and 26, called herein cross-stays, extend from the uprights inward and downward and from upright to upright. Each has eyes at its ends and includes a turnbuckle or turnbuckles. The bracket 27 riveted to upright 1 engages with the eye at the upper end of the cross-stay 25, and a like bracket 28 riveted to the upright 2 engages with the eye at the upper end of the cross-stay 26. The bracket 29 riveted to upright 1 engages with the eye at the lower end of stay 26, and a like bracket 30 riveted to upright 2 engages with the eye at the lower end of stay 25. The stays 25 and 26 cross one another midway between the uprights and there pass through the hanger 31 (Fig. 1.) This hanger, which is stiff and in which

the cross-stays are clamped, is composed of the grooved plates 32 and 33 bolted together by the bolts 34, these plates having the shapes represented in Figs. 4, 5 and 6. Their lower portions form a shackle through which the bolt 35 passes.

The stays 36 extend from the upright 1 inward and downward to cross-stay 26 and are attached to it by means of the hangers 37 (Fig. 1) which form the lower ends of these short stays. The cross-stay passes through and is clamped in these hangers, each of which consists of separable sections 38 and 39 bolted together by bolts 40 (Figs. 8 and 9.) The short stays 41 extend from the upright 2 to the cross-stay 25 and are attached to it by means of the hangers 42 (Fig. 1) in which the cross-stay is clamped and which are like the hangers 37. These hangers 37 and 42 also are stiff. The short stays 41 include turnbuckles and are put under such tension that the cross-stays are bent upward between the hanger 31 and the uprights, as appears by Fig. 1.

A pair of rafters is attached to the cross-stays by means of the central hanger 31 and the hangers 37 and 42, each rafter being composed of beams arranged continuously; or in other words so that each forms a continuation of another, and the beams being secured together by bolts or other connecting-devices. The beams 43 form one of the rafters and the beams 44 form the other rafter. These beams may be either wood or metal. One rafter is attached at its lower end to the upright 1 close to the lower end of the cross-stay 26 and the other rafter is attached at its lower end to the upright 2 close to the lower end of cross-stay 25. This may be done by bolting the rafters to the brackets 29 and 30 by means of bolts 45 passing through the rafters and brackets (Fig. 7.) At their upper ends the rafters fit in the central hanger 31 and are held therein and connected together by the bolt 35. The beams of each rafter are attached either to the hangers 37 or the hangers 42. The beams fit in the hangers and are secured to them by bolts 46, as appears in Figs. 8 and 9. The beams may be faced at their ends with metal plates 47 and 48, each pair of plates 47 fitting between a pair of plates 48 fast on and projecting from the adjoining beam, and the bolts which connect the beams together and to the hangers may pass through those plates (Figs. 6-9.) The beams of each rafter form angles in the hangers 37 or 42, each angle being only a little less than a hundred and eighty degrees, and the vertices of these angles are downward so that each rafter bends downward and throughout almost its whole length is below a straight line which cuts it at both ends. The cross-stays, rafters, and hangers, which are also struts, form what are essentially two inclined trusses secured

together at their upper ends midway between the uprights, and secured at their lower ends to the uprights, and the outer stays 12 and 15 counteract the stresses imposed on the uprights by the cross-stays at their lower ends, as well as some stresses imposed on the uprights by both the cross-stays and rafters, as will be hereinafter explained.

10 The frame-unit may be constructed or partly constructed while the uprights lie on the ground and then the assembled parts may be erected by swinging the uprights on the pins 7 and 8, and when a building is taken down each frame-unit may be swung on the pivotal pins of the uprights until it lies on the ground before its parts are disconnected from one another.

20 The frame-units of a series are fastened together by beams 49 which may be of wood or metal, and the framework is stiffened at places on both sides by stays 50 extending from one upright to an adjacent upright.

25 The joists 51 are laid on the rafters and braced as joists commonly are, and are covered with corrugated sheet iron, or with boards and tarred paper, or some other roofing-material.

30 The beams 52 form extensions of the rafters, and are attached to the uprights or beams fastened thereto, and to posts 53. The roof may be extended to the outer ends of the beams 52 and the side walls of the building may consist of corrugated iron sheeting or other suitable material fastened to the posts 53. Of course a building may be closed at either or both of its ends by walls such as the wall 54 (Fig. 11) fastened to the roof and the uprights of the end units of the series and having in it doors and windows.

35 It will be understood that many of the details of the frame-unit and framework described may be changed or replaced by others differing from them in form, and that modifications of the frame unit may be made, within the limits fixed by the claims, to adapt the invention to small as well as large buildings, and to buildings comprising 40 peculiar features of construction.

45 When it is desirable to erect two large buildings and place them side by side and close together, it is expedient, in order to save materials, labor and expense, to utilize 50 a series of frame-units like the duplex frame-unit represented in Fig. 12. This is composed of the three uprights 55, 56 and 57, the outer stays 58, 59 and 60, 61, the cross-stays 62 and 63 attached to uprights 55 and 56, the cross-stays 64 and 65 attached to uprights 56 and 57, the short stays 66, 67, 68, and 69, and the two pairs 70 and 71 of rafters attached to the cross-stays. Each detail of its construction is like that of a similar feature of the frame unit above described

and will readily be understood, it is believed, without the aid of further explanation. When the framework of a building or buildings includes a series of frame-units like this duplex frame-unit, the units of the series 5 are united by beams like the beams 49 (Fig. 10) extending lengthwise of the series, and are braced by stays such as the stays 50 (Fig. 10.) But Fig. 12 illustrates a variation in the foundations of the uprights. These 10 foundations are here shown as walls 72, 73 and 74, two of them, 72 and 74, forming the side walls of the double building, and the other, 73, forming a central partition extending from end to end of the building. 15 The uprights may extend into or through the walls or thickened portions 75 thereof (Fig. 13) or may stand on them. It will be seen that uprights 55 and 56 form a pair 20 and that stay 64 extends outward and downward from upright 56. Also it will be seen that uprights 56 and 57 form a pair and that the stay 63 extends outward and downward from upright 56. Therefore the stays 25 63 and 64 are essentially outer stays as well as cross-stays, their action on upright 56 being substantially the same as that of the long outer stays on the uprights of the frame-unit 30 particularly described above.

It now will be evident, it is believed, that 35 this duplex frame-unit may be extended by adding to it other uprights, stays and rafters, and that a series of such extended frame-units may form trusses of the framework of a large number of buildings placed side 40 by side.

By practicing this invention it is feasible 45 to construct a very large building, devoid of any interior obstruction, so that the roof shall not only be properly supported but also 50 shall be reinforced in a way calculated to prevent it from being torn off by a violent wind or some force acting on it from within the building and tending to lift it. A force, such as wind-pressure, tending to 55 lift the roof would be resisted by those parts of the cross-stays which extend from the peak of the roof to the uprights. They tend to prevent the central hanger from moving upward and each cross-stay tends to prevent 60 the other from moving upward, while the stays 12 and 15 tend to prevent the uprights from springing or bending at the lower ends of the cross-stays. Moreover, the 65 hangers or struts 37 or 42 would help each rafter to withstand pressure exerted on it from beneath and so would the downward curvature of the rafter, which is essentially an inverted arc. The curved rafters would 70 not buckle in cases when straight rafters 75 otherwise like them in construction probably would.

Buildings in which this invention is utilized may be erected and taken down by unskilled laborers, there being neither framing 80

nor riveting to be done or undone by them, and the materials for such buildings may be prepared and collected and transported with facility and at comparatively low expense.

5 Having thus described my invention, what I claim as new and desire to secure by Letters Patents, is:

1. In framework forming part of a building and including a series of frame-units each comprising a pair of rigid uprights to which are attached stays that extend outward and downward therefrom, the combination with the uprights of cross-stays by which the uprights are tied together, and 10 a pair of rafters, the cross-stays extending from the uprights inward and downward and lengthwise of the rafters and being attached to the uprights close to the lower ends of the rafters, and the pair of rafters 15 and cross-stays being fastened together at the upper ends of the rafters and where the stays cross and at other places between the upper and lower ends of the rafters, and the cross-stays being connected to the uprights by short stays extending inward and 20 downward from the uprights.

2. In framework which forms part of a building and includes the elements of the combination defined in claim 1 and in which 25 each of the rafters is composed of beams arranged continuously and fastened together, the combination with those elements of rigid hangers which are attached to and extend

below the cross-stays and to which the rafters are attached at the meeting ends of 35 the beams.

3. Framework which forms part of a building and includes the elements of the combination defined in claim 2 and in which each beam forms an angle with the next and 40 the cross-stays are bent upward between the ends of the rafters, the vertex of the angle formed by any two beams of a rafter being below a straight line which cuts the rafter at both of its ends.

4. In framework forming part of a building and including a series of frame-units each comprising pairs of rigid uprights, the two uprights at the ends of the frame-unit being connected to anchors by outer stays, the 45 combination with the uprights of each pair of cross-stays by which the uprights are tied together, and a pair of rafters, the cross-stays extending from the uprights inward and downward and lengthwise of the rafters 50 and being attached to the uprights close to the lower ends of the rafters, and the pair of rafters and cross-stays being fastened together at the upper ends of the rafters and where the stays cross and at other places between the upper and lower ends of the 55 rafters, and the cross-stays being connected to the uprights by short stays extending inward and downward from the uprights.

BENJAMIN W. LEVITAN.
